UNITED STATES PATENT OFFICE.

FRANK NICOLAUS WEIS AND WILLIAM CHRISTIAN WEIS, OF MONROE, MICHIGAN,
ASSIGNORS TO THE WEIS-VAN WORMER COMPANY, A CORPORATION OF MICHIGAN.

PAPER-BOTTLE-SEALING MACHINE.

1,069,915.

Specification of Letters Patent. Patented Aug. 12, 1913.

Application filed November 27, 1911. Serial No. 662,642.

To all whom it may concern:

Be it known that we, FRANK N. WEIS and WILLIAM C. WEIS, citizens of the United States, residing at Monroe, in the county of Monroe and State of Michigan, have invented certain new and useful Improvements in Paper-Bottle-Sealing Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

The bottles upon which our machine is intended to operate are intended, among other things, and, more particularly, to contain milk, and are composed of paraffined paper. The bottles may be of any desired shape in cross-section, but preferably are square. The tops of the bottles may be flat or rounded but are,—to facilitate emptying,—preferably slightly conical, the cone being truncated by a round hole through its apex. The bottle being filled, it is necessary that it be closed and hermetically sealed, and—when large quantities of milk or other liquids are handled—it is necessary that this be done rapidly and cheaply.

To effect this is the object of the present invention.

Our invention is designed, more particularly, to close and hermetically seal a number of these bottles,—say a dozen,—simultaneously and by a single stroke of a lever.

The sealing devices to be applied consist of cup-shaped flanged stoppers composed of paraffined paper. The flange of this stopper rests upon the margin of the hole, above mentioned, with the cup-shaped body-portion projecting down through the top of the bottle.

A further object of our invention is to provide means for expanding this cup-shaped body-portion within the bottle so that the stopper may not be removed without visibly rupturing the mouth of the bottle, (to prevent improper re-use,) and, at the same time, to press the flange of the stopper down upon the top of the bottle and, by the application of heat, to melt the paraffin upon the contacting surfaces of the stopper and bottle, thus further securing the stopper in place and hermetically sealing the bottle.

We accomplish the objects above indicated by means of the devices, construction and arrangement of parts hereinafter described, and shown and illustrated in the accompanying drawings, in which—

Figure 1 is a front-elevation of our machine, showing one of the presser-sleeves or plungers—hereinafter referred to—in central vertical section, to show its internal arrangement, also disclosing one of the paper receptacles hereinafter referred to together with its stopper in central vertical section, also the case or box which holds the bottles, which case is broken away to exhibit its contents; Fig. 2, a side-elevation of our machine seen from the left in Fig. 1; Fig. 3, a top-plan view of the same; Fig. 4, a central vertical sectional elevation, on an enlarged scale, of the presser-sleeve or plunger and the expander hereinafter referred to, detached, with the expander collapsed, and Fig. 5, the same showing the expander in its expanded form.

Like numerals indicate like parts throughout the drawings.

A pedestal 1 has bolted to its top a table 2, having at two opposite sides an inwardly turned flange 2^a serving as guides for a sliding table 3 having upwardly projecting stops 3^a spaced apart exactly such distance as to receive the bottle-case 4. This box, in the present instance, is adapted to hold three rows of bottles *a*, there being four bottles in each row. The sliding table 3 is arranged to move toward and away from the operator, at the front of the machine, that is, to the right of Fig. 2. The inward movement of the table 3 is limited by set-screws 3^b, the adjustment of which serves to stop the several bottles to be closed and sealed in exact vertical alinement with their respective sealing devices.

At opposite sides of the table 2 are standards 5 and at its rear end is a standard 6. These three standards support at their top a flat rectangular steam-chest 7, connected with inlet and outlet steam pipes 8. Through this steam-chest are vertical cylindrical passages 9,—in the present instance twelve in number,—in each of which reciprocates a device now to be described.

10 is a cylindrical presser-sleeve or plunger securely fastened at its top by nuts 11 to a plate 12, as shown in detail in Figs. 4 and 5. The bottom of the presser-sleeve 10 is shaped

to conform to the top of the bottle *a* and the cavity of the cup-shaped paper stopper *b*. The sleeve 10 is bored axially for the reception of a plunger 13 which reciprocates 5 therein. At its upper end the plunger 13 is threaded and by means of nut 14 is securely attached to a horizontal plate 15. At its lower end the plunger 13 flares downwardly, as at 16. The bore of the sleeve 10, 10 at its lower end, is enlarged to form a chamber 17 in which is a sleeve 18 surrounding loosely the plunger 13 and held rigidly connected with the sleeve 10 by means of screw 19. The sleeve 18 is split, as at 20, to form 15 downwardly projecting resilient fingers 21 the lower ends of which are turned outwardly, as at 22. The fingers 21 at their lower ends embrace and conform to the inclined portion 16 of the plunger 13.

20 If a paper bottle, such as is illustrated in Figs. 4 and 5, be placed directly beneath and in alignment with presser-sleeve 10 and if the sleeve be now depressed, the flange of the stopper *b* will be pressed tightly down upon 25 the top of the bottle, as illustrated in these figures. This movement of the presser-sleeve 10, and with it the plunger 13, is accomplished by the movement of the plates 12 and 15 which carry all of the plungers, 30 which movement is effected by the mechanism now to be described.

Secured to opposite sides of the steam-chest 7 are upright arms or brackets 23 at the top of and between which is journaled a 35 shaft 24. Near opposite ends of this shaft are rigidly secured, as at 25, forwardly projecting arms or levers 26, between the forward extremities of which is journaled, as at 27, a shaft 28. Rigidly secured to the 40 shaft 28, midway of its length and extending forwardly within reach of the operator, is a hand-lever 29.

30-30 are arms rigidly secured at their forward ends to the shaft 28 and extending 45 backwardly and overlapping, as at 31, a portion of the levers 26. Pivotal secured to the lever 26, as at 32, (see Fig. 2) are rods 33 which pass up through the overhanging portions 31 on the arms 30. Each 50 of the rods 33 is threaded at top to receive a nut between which and the part 31 is a coiled compression-spring 34. Pivotal secured to the arm 26, as at 35, are downwardly extending links 36 which, at their 55 lower ends, are pivotally secured between lugs 37 formed on the top of the plate 12. Pivotal secured, as at 38, to the arms 30 are downwardly extending links 39 pivotally secured between lugs 40 on the top of the 60 plate 15. Now, to lower the presser-sleeves 10 upon the top of the bottles, the hand lever 29 is pressed downwardly, to the position indicated by the lower dotted lines in Fig. 2, swinging the arms 26-30 upon the 65 fulcrum furnished by the shaft 24, and,—

through the links 36 and 39,—lowering the plates 12 and 15 together. When the presser-sleeves 10 strike the top of the bottles *a* with sufficient force, adjusting screws 41 in plate 12 come in contact with the top 70 of the steam-chest 7 and arrest the further downward movement of the plate 12. A further downward movement of the hand-lever 29 overcomes the resistance of the compression-springs 34 and now the arms 30, 75 fulcrumed on the shaft 28, swing upwardly and,—through the links 39—lift the plate 15 and with it the several expansion-plungers 13 secured thereto. This upward movement 80 of the expansion-plungers, by their wedge-like action upon the resilient fingers 21 forces the lower ends 22 of these fingers horizontally outwardly thus expanding the bodies of the stoppers within each of the bottles and forming a circumferential ridge, 85 on the stopper just inside the margin of the mouth of the bottle, thus preventing the removal of the stopper except by visibly rupturing the mouth of the bottle.

The shaft 24 carries, rigidly connected therewith, as at 42, an arm 43 at the outer end of which is a counter-weight 44. When the hold upon the hand-lever 29 is released, the springs 34 depress plate 15 and plungers 13, thus collapsing the expanders; the counter-weight rotates the shaft 24 which throws upwardly the arm 26 which, in turn, catches the arm 30. Now the shaft 28 and the hand-lever are thrown upwardly into the position indicated by the upper dotted 100 lines in Fig. 2, thus lifting plates 12 and 15 and the several plungers out of the way so that the box 4 and its now sealed contents may be withdrawn, leaving the machine ready for the reception of another box of 105 bottles.

It should be understood that the steam circulating through the steam-chest 7 keeps the plungers and expanders quite hot, and that when these heated parts come in contact with the paraffined surfaces of the bottle and stopper, the paraffin is melted to seal the package. The heat of the expanders also assists in the stretching and setting of the paper stopper in its expanded form.

Having described our invention, what we claim and desire to secure by Letters Patent is,—

1. In a device of the described character, a presser-sleeve, secured within the presser-sleeve an expander consisting of a sleeve split longitudinally to form fingers, said fingers having out-turned extremities, a plunger disposed axially of said two sleeves and adapted by its backward movement to spread said out-turned extremities, and means for forwardly actuating said two sleeves and the plunger in unison and for actuating the plunger backwardly independently of the two sleeves.

2. In a device of the described character, a presser-sleeve, secured within the presser-sleeve an expander consisting of a sleeve split longitudinally to form fingers, said 5 fingers having out-turned extremities, a plunger disposed axially of said two sleeves and adapted by its backward movement to spread said out-turned extremities, and means for forwardly actuating said two 10 sleeves and the plunger in unison and for actuating the plunger backwardly independently of the two sleeves, combined with chambered guides for said presser-sleeves and means for heating the guides.
- 15 3. In a device of the described character, a chambered presser-sleeve having at its lower end an annular recessed rim adapted to enter—in part—the mouth of a bottle of the described character, an expander which 20 projects below the annular rim, a rod extending into the chamber of the sleeve and adapted by its backward movement to actuate the expander, means for actuating the sleeve, and means for actuating the rod.
- 25 4. In a device of the described character, a member which carries a presser-sleeve, within said sleeve an expander, another member which carries a rod disposed axially of said sleeve for actuating the expander, 30 and means for actuating forwardly said two carrying members in harmony and independent means for actuating the rod-carrying member backwardly.
- 35 5. In a device of the described character, a plate, a series of presser-sleeves carried by said plate, an expander secured within each of said sleeves, another plate, a series of plungers carried by the latter plate and disposed axially of the sleeves and expanders 40 and adapted by their backward movement to actuate the expanders, and means for actuating said two plates forwardly in unison and for actuating one plate backwardly independently and during the pause 45 of the other.
6. In a device of the described character, two plates disposed horizontally, one above the other, a lever, pivotal connections intermediate the lever and the plates where- 50 by said two plates are lowered in unison with the initial movement of the lever and
- whereby the further movement of the lever retracts one of said plates independently of the other, combined with pressing devices and expanding devices carried by said 55 plates.
7. In a device of the described character, a shaft, arms secured to the shaft, a second shaft journaled upon said arms, arms secured to the second shaft, spring connec- 60 tions between the former and latter arms, a lever secured to the second shaft, a plate, link-connections between the plate and the arms first mentioned, a second plate, and link-connections between the second plate 65 and the arms of the second shaft, combined with co-acting pressing devices and expanding devices carried by said plates.
8. In a device of the described character, a group of equi-distant symmetrically ar- 70 ranged presser-sleeves, expanding devices and plungers mounted within and co-acting with the sleeves, means for actuating the sleeves and expanders forwardly in har- 75 mony and for retracting said plungers independently of the presser-sleeves, and a movable support adapted for the reception of a box conforming to said group and which permits the movement of such box into and out of operative relation to said 80 group.
9. In a device of the described character, a group of equi-distant symmetrically ar- 85 ranged presser-sleeves, expanding devices and plungers mounted within and co-act- 90 ing with the sleeves, means for heating the sleeves, means for actuating the sleeves and expanders and plungers forwardly in har- 95 mony, means for retracting the plungers independently of the movement of the presser-sleeves, and a movable support adapted for the reception of a box conforming to said group and which permits the movement of such box into and out of operative relation to said group.

In testimony whereof we affix our signatures in presence of two witnesses.
